UNITED STATES PATENT OFFICE.

WILLIAM F. DRAPER AND JONAS NORTHROP, OF HOPEDALE, MASSACHUSETTS; SAID NORTHROP ASSIGNOR TO SAID DRAPER.

LOOM-SHUTTLE.

No. 909,771.

Specification of Letters Patent.

Patented Jan. 12, 1909.

Application filed February 13, 1908. Serial No. 415,637.

To all whom it may concern:

Be it known that we, WILLIAM F. DRAPER and JONAS NORTHROP, citizens of the United States, and residents of Hopedale, county of 5 Worcester, State of Massachusetts, have invented certain new and useful Improvements in Loom-Shuttles, of which the following is a full, clear, and exact specification.

Our present invention relates more particularly to loom shuttles adapted for use in 10 automatic filling-replenishing looms in which a fresh filling-carrier or bobbin is inserted automatically in the shuttle to replenish the running filling when necessary. Such shuttles have an opening in which the bobbin enters, and holding means to engage the head or 15 butt of the bobbin and maintain it in proper position in the shuttle. The holding means comprise jaw-like members made integral 20 with each other and fastened in the shuttle, the free ends of the jaws gripping the bobbin head, and an inclined guide is inserted between the bases of the jaws with the object of forcing the shuttle backward into 25 position to bring the jaws into position to receive the bobbin-head if the shuttle is misplaced in the shuttle-box. Such jaws are 30 expensive to make, they are relatively and necessarily stiff and hard in their action and require very considerable force to be used to 35 insert the bobbin and drive out the preceding one.

Our present invention has for one of its 35 objects the improvement of the holding jaws, whereby they can be made very cheaply, and also to make the insertion and ejection of the bobbin easier.

Another object of the invention is to provide such a jaw structure that the inclined 40 guide may be eliminated. This guide is necessary with holding-jaws as at present constructed, but it is objectionable in that it tends to break bobbins which strike upon it, and furthermore, when the head or butt 45 strikes the inclined guide the tip end of the bobbin is frequently thrown down below the bottom of the shuttle. Although it usually recovers itself it breaks the filling in many cases, and our present invention overcomes 50 these objectionable features.

To compensate for the different positions the shuttles may assume in the shuttle-box when filling is changed we have provided the jaws with an increased number of 55 recesses or notches to engage the usual annular

projections or rings on the bobbin-head, so that the bobbin will be caught and held when it descends at any one of a number of different points relative to the jaws.

Figure 1 is a top plan view, partly broken out, of the holding end of a loom shuttle of the type referred to, with holding means embodying our invention mounted therein; Fig. 2 is a partial longitudinal vertical section on the line 2—2, Fig. 1; Fig. 3 is a horizontal section on the line 3—3, Fig. 2 with the butt of the bobbin in dotted lines; Fig. 4 is a cross-section on the line 4—4, Fig. 1, looking toward the left; Fig. 5 is a perspective view of one of the holding jaws, detached; Fig. 6 is a similar view of the retaining member to be referred to; Fig. 7 is a plan of the blank from which the retaining member is made.

The shuttle-body is represented at 1, having an elongated opening 2 from top to bottom for the reception of the filling-carrier or bobbin, the head 3 of which is shown in Fig. 1 as provided with usual annular projections or rings 4, three of such rings being generally employed. The shuttle-body is provided with a longitudinal recess 5 communicating with the bobbin-receiving opening 2, the recess being quite narrow, see Fig. 4, and open at the top, with undercut portions or 80 grooves 6 in its side walls near the top. By making the recess narrow as little of the wood is removed as is possible, strengthening 85 the shuttle at the end, where it is needed.

We make the holding jaws for the bobbin 90 separate, and alike, so that they are reversible, avoiding the making of rights and lefts, and as the jaws are stamped or struck up from plate-metal they can be made very 95 cheaply.

One of the jaws is shown separately in Fig. 5, the free end or jaw portion 7 having a number of upright pocket-like notches 8 formed on its inner face, six being shown, to engage the bobbin rings 4 when the bobbin is 100 inserted in the shuttle, and the base of the jaw portion is bent inward at 9 and terminates in a flat shank 10, apertured at 11. The jaw member is stamped or died out from plate metal and is of the same width from one to 105 the other end, and the setting in of the shank 10 brings its inner face in the median line of the shuttle when the jaws are assembled, see Fig. 3, the jaw portions proper, as 7, slightly converging toward their extremi- 110

ties, when the shuttle is empty, but in Fig. 3 said jaws are shown in the position assumed when grasping the butt of the bobbin, which latter is indicated by dotted lines. 5 The metal of which the jaw is made is sufficiently resilient or springy to yield readily for the incoming or outgoing bobbin while yet possessing sufficient stiffness to hold the bobbin properly in the shuttle. The shanks 10 10 are placed face to face with the holes 11 registering, between side pieces of a retaining member, which act as fillers to tightly fill the space between the outer faces of the shanks 10 and the walls of the recess 5, and 15 a clamping bolt 12 is passed transversely through the shuttle-wood and through the holes 11 and corresponding holes in the fillers, a nut 13 holding the bolt in place.

The retaining member, shown separately 20 in Fig. 6, is made of a single piece of plate metal stamped out first in the form of the blank shown in Fig. 7, and afterwards bent along the dotted lines into the shape shown in Fig. 6. Said retaining member comprises 25 parallel and substantially rectangular top and bottom portions 14, 15, the top being wider than the bottom and extending laterally beyond the fillers 16, which are bent up from the side edges of the bottom portion 15 30 parallel to each other and just leaving a sufficient space between them to tightly receive the shanks 10, the fillers having bolt holes 17. A rigid connection 18 forms a continuation of the top and bottom portions of the 35 retaining member, at the outer end thereof, and crosses the ends of the jaw shanks, limiting their movement when inserted between the fillers, Figs. 2 and 3. At its front end the top 14 is narrowed and bent down to 40 form a depending tongue 19, overlapping at its lower end a segmental enlargement 20 of the bottom portion 15 of the retaining member, the lower edges of the bent bases 9 of the jaws resting upon the segmental enlargement 20.

The fillers form a rigid-sided, narrow housing in connection with the top 14 and bottom 15, which housing receives with a tight fit the jaw shanks 10, the holes 11 and 50 17 all registering, the jaws being accurately positioned when the retaining member is placed in the shuttle.

The parts having been assembled as described are now put in the shuttle, the filled 55 housing being pushed into the recess or socket 5 and snugly filling it from side to side, the wider top 14 of the housing sliding into the undercut grooves 6, as shown in Fig. 4, while the part 15 rests on the bottom of 60 the recess. The bolt 12 is then applied and by the nut 13 is securely fixed, the parts being fixedly clamped and held in the shuttle-body. Fore and aft movement of the parts is prevented by the bolt, and the snug 65 fit of the housing in the recess 5 holds the

retaining member from any lateral or up and down movement, the jaw bases being securely held between the top and bottom members 14 and 15, and between the fillers 16.

While the shanks are rigidly held in the shuttle the jaws proper are free to spring or separate for the admission or discharge of a bobbin, and this housing and closing movement is much easier than when the jaws are integrally connected. 75

As usual the sides of the shuttle are inferiorly recessed at 21, to give free play to the jaws, the walls of the two recesses being continued around the end of the bobbin opening 2 to the upright edges of the recess 80 5, but the shuttle wood is carried forward to the front edge of the bottom member 15 of the retaining member, to form an additional support for the segmental enlargement 20 and resist the downward thrust when a bobbin is inserted in the shuttle, substantially 85 as usual.

It will be seen that the jaws are quite long, and as they are provided with a relatively 90 large number of notches there is considerable leeway permitted for the position of the incoming bobbin relatively to said jaws.

The rings on the bobbin head may engage 95 the notches either at the center of the jaws, at their inner ends, or at their outer ends, but in any case the bobbin will be firmly and properly held, and positioned, obviating the use of an inclined guide and thus doing away with the objections to the use of such a guide. 100

The construction is simple, cheap and efficient, and the assembling of the parts and the securing of the same in the shuttle is quickly and easily accomplished.

Having described our invention what we 105 claim as new and desire to secure by Letters Patent is:—

1. A loom shuttle provided with a bobbin opening and having a longitudinal recess in the shuttle-wood at one end of said opening, two oppositely positioned, separate and like resilient holding jaws having their free ends notched to receive the rings on the head of a filling-carrier, the shanks of the jaws being set in from the notched portions and placed in parallelism adjacent to each other in said recess of the shuttle-body, and means to fixedly clamp the shanks in position, said means including metallic fillers interposed between the shanks and the sides of the recess. 110 115 120

2. In a loom shuttle having a recess in the shuttle-wood, two separate and reversible resilient holding jaws shaped to receive and hold the head of a filling carrier, each jaw having a flat shank set in from the plane of 125 its holding portion, and means to coöperate with both jaws and fixedly retain them in the shuttle, said means including a member having parallel side portions between which the shanks of the jaws are inserted, 130

the said member being inserted in the recess in the shuttle-wood.

3. In a loom shuttle having a recess in the shuttle-wood, two separate and like holding-jaws having their opposite free ends notched to receive annular projections on the head of a filling-carrier, and means to fixedly clamp the jaws in position in the shuttle, said means including a member detachably inserted in the recess in the shuttle-wood, and in which member the jaws are detachably mounted.

4. In a loom shuttle having a longitudinal recess in the shuttle-wood, two separate and like holding-jaws having their oppositely located and resilient free ends shaped to engage and hold the head of a filling-carrier, and means to fixedly hold the jaws in operative position in the shuttle, said means comprising a retaining member in which the jaws are detachably mounted, said member being inserted in the recess in the shuttle-wood, and a bolt extended through said member, the portions of the jaws therein, and the shuttle-wood at opposite sides of the recess.

5. A loom shuttle having a bobbin opening and a longitudinal recess in the shuttle-wood at one end thereof, two separate holding-jaws having their free ends notched to engage rings on the bobbin head and having their shanks set in from the planes of their free ends and placed face to face, a retaining member having parallel side portions interposed between the sides of the recess and the jaw shanks and having top and bottom portions overlapping the upper and lower edges of said shanks and the side portions, the bottom portion of said retaining member having an extension upon which the bases of the jaws are supported, and a holding bolt extended transversely through the jaw shanks and the side portions of the retaining member.

6. A loom shuttle having a bobbin opening and a longitudinal recess in the shuttle-wood at one end thereof, two separate holding-jaws having their free ends shaped to grasp the head of a bobbin and having their shanks set inward and inserted in the recess face to face, metallic fillers between the shanks and the sides of the recess, said fillers forming integral parts of a retaining member having top and bottom portions to hold

between them the shanks of the jaws at top and bottom and rigidly connected at their outer ends, and a bolt extended transversely through the shuttle body, the shanks and fillers, to fixedly secure the same in the shuttle.

7. A loom shuttle having a bobbin opening and a longitudinal recess in the shuttle-wood at one end thereof, the recess having grooves in its side walls, and a retaining member comprising parallel top and bottom portions rigidly connected at their outer ends, the top portion being wider and adapted to enter the grooves in the recess while the bottom portion seats on the bottom of the recess, and parallel fillers upturned from the side edges of the bottom portion of said retaining member, said bottom portion having a segmental enlargement at its inner end, combined with two separate holding-jaws having their free ends notched to engage rings on the bobbin head and having their shanks set in and inserted face to face between the fillers, the bases of the jaws resting on the segmental enlargement, and a holding bolt extended transversely through the jaw-shanks and fillers to secure the same in the shuttle.

8. A loom shuttle having a bobbin opening and a longitudinal recess in the shuttle-wood at one end thereof, combined with two separate holding-jaws having their free ends shaped to grasp the head of a bobbin and having their shanks set in and placed face to face, a one-piece retaining member adapted to embrace the outer sides, top and bottom edges of the jaw shanks, and provided with an enlargement to support the bases of the jaws, said retaining member being adapted to enter the recess, and a holding bolt crossing the recess and passing through the jaw shanks and the side portions of the retaining member, to hold said member and the jaws rigidly in the shuttle.

In testimony whereof we have signed our names to this specification in the presence of two subscribing witnesses.
